COMBINED RECORD PLAYER HOUSING AND STAND

Harvey K. McQuarrie, Kitchener, Ontario, Canada, assignor to Electrohome Limited, Kitchener, Ontario, Canada

Filed Feb. 21, 1973, Ser. No. 334,463

Term of patent 14 years

Int. Cl. D14—01
U.S. Cl. D56—4 R

FIG. 1 is an elevational view of a combined record player housing and stand showing my new design;

FIG. 2 is a top plan view;

FIG. 3 is a bottom plan view; and

FIG. 4 is an enlarged scale perspective view of a fragmentary portion of the tambour ornamentation band of FIG. 1.

I claim:

The ornamental design for a combined record player housing and stand, as shown and described.
